PAPER CUTTING AND TRIMMING MACHINE
AND THE LIKE

Emil L. Mueller, Rutherford, N. J.

Application September 22, 1931, Serial No. 564,378

4 Claims. (Cl. 164—58)

This invention relates to an improvement in paper cutting and trimming machines and the like, and its object is to provide means to facilitate the easy and convenient attachment and removal of the cutting blade or knife of such machines.

The cutting blades or knives of machines of this type are usually very heavy and unwieldy and the extreme keenness of their cutting edge renders them dangerous and difficult to handle especially in getting them into and out of operative position within the machine, it being usually necessary to employ the services of two or more men to perform this operation even in machines of only moderate size. It is accordingly a purpose of the present invention to provide means to simplify and expedite this operation.

A more specific object is to provide means whereby the knife may be temporarily supported during the time while its retaining bolts are being removed or replaced, as well as during the time while the knife is being moved or adjusted into a position wherefrom it can be readily lifted out of the machine, or during the time while the knife is being moved or adjusted back again into position for the insertion of the holding bolts.

A further detailed object is to provide means to facilitate the making of the fine adjustments, both vertically and horizontally, which are usually required to bring the knife into position for receiving its holding bolts.

A further detailed object is to provide a separately formed attachment readily attachable to or detachable from the machine for use in facilitating the attachment and removal of the knife.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawing which is to be taken as a part of this specification, and in which I have shown merely a preferred form of embodiment of the invention:—

Fig. 1 is a front elevational view of a portion of a paper cutting machine and illustrating the same as being supplied with parts proposed by the present invention, preparatory to removal of the knife.

Fig. 2 is a view similar to Fig. 1 but showing the knife as it appears when disconnected and ready for being lifted out of the machine.

Fig. 3 is a transverse detail sectional view upon the plane of line III—III of Fig. 1, and

Fig. 4 is a similar sectional view upon the plane of line IV—IV of Fig. 2.

Referring to the drawing for describing in detail, the exemplary structure illustrated therein, the reference character L indicates generally the frame work of a paper cutting machine. The bed plate of the machine is indicated by the reference character G.

Vertically slidable within the frame L is the usual clamp bar H and knife carrying bar A, these parts being operated in appropriate manner as is customary with such machines, as for instance by means of the links 1—1 and 2—2 shown in the drawing as being connected respectively with the clamp bar and with the knife carrying bar, it being understood of course that these links extend downwardly into connection with suitable mechanism not illustrated but which is usually foot controlled so that the operator has instant control of the independent movements of the clamp bar and of the knife carrying bar, all as is well known in machines of this type.

The knife blade is indicated by the reference character 3. It is formed separate from the knife carrying bar A and in use is held rigidly connected with the bar A by means of a series of bolts 4—4 which extend through apertures 5 of the bar A and engage within threaded openings 6 of the knife.

In attaching the knife carrying bar A it is of course necessary to first move the knife into position so that the openings 6 register with the openings 5 and then the knife must be held in this position while the bolts are being placed. Also in removing a knife from connection with the bar A it is necessary to hold the knife against falling heavily when the last bolt has been removed, or from straining upon the last two or three bolts being removed. In view of the keenness of the cutting edge of the knife, and the weight of the knife, both of these tasks are ordinarily considered very difficult and dangerous and must usually be performed with extreme care to prevent both injury to the workman and injury to the knife.

According to the present invention however, it is proposed that an attachment be provided in the form of a rest to support the weight of the knife, and to so arrange this rest that the knife, while supported thereon, may be moved easily into or out of its proper co-operative relation with the knife carrying bar.

In the instance illustrated this rest is provided

in the form of a pair of discs as 7 and 8 made up separate from the machine but adapted to be easily attached thereto, there being bolts as 9 extending through the discs and having threaded rear ends adapted for engagement within threaded apertures 10 provided to receive them in a portion of the clamp bar H which extends below the lower edge of the knife 3. The discs 7 and 8 each have beveled peripheral surfaces as 11 shaped and disposed so as to mate with and receive the beveled lower edge of the knife 3, the discs being preferably cut away slightly at their rear surfaces as at 13 so as to stand free of the keen cutting edge of the knife at all times.

15 The apertures of the discs through which the bolts 9 extend are preferably placed so as to be slightly eccentric with respect to the discs, and the discs are intended to be rotatable upon said bolts when manual force is applied as through the 20 medium of the thumb wings 13 illustrated.

The purpose of making the discs eccentric upon their supporting bolts is to provide means whereby the operator may conveniently elevate or depress, to a sufficiently slight and accurate degree, 25 one or the other of the ends of the knife particularly during the operation of returning the knife into position accurately mating the apertures 5 of the bar A, it being noted in this connection that the two discs are spaced apart along 30 the length of the clamp bar and of the knife carrying bar so that they stand adjacent to opposite ends of the knife.

The purpose of making the discs rotatable upon their supporting bolts is two-fold, first, to facilitate the adjustment just referred to, and, second, to enable the operator, by manual rotation 35 of the two discs simultaneously in the same direction, to adjustably move the knife longitudinally in either direction according to the direction of 40 rotation of the discs.

Assuming it is desired to remove the knife 3; the workman proceeds by first attaching the present attachment, that is the two supporting discs, by means of their bolts 9, onto the clamp- 45 ing bar H. If the discs are not already in close engagement with the beveled edge of the knife he then rotates one or both thereof so as, by reason of the eccentric mounting of said discs, to bring them into firm supporting engagement 50 with the knife. This done the knife retaining bolts 4 are unscrewed and removed. These bolts may be all removed since the weight of the knife is no longer supported by them but is now carried upon the two discs constituting the present at- 55 tachment.

After the bolts 4 have all been removed then the workman performs the necessary operation to effect a lowering of the clamp bar, and hence of the knife, from the position shown in Figs. 1 60 and 3 to the position shown in Figs. 2 and 4, the knife being now entirely free of its engagement with the knife carrying bar A. In this position the knife may be readily lifted away for the making of repairs, for sharpening etc.

65 When it is desired to return the knife into operative connection with its carrying bar A the knife is first placed upon the two supporting discs, the parts being as in Figs. 2 and 4. Thereupon the workman performs the necessary operation to cause the clamp bar and with it the two discs and the knife to be lifted into approximately the position wherein the threaded openings 6 of the knife will mate the apertures 5 of the knife carrying bar A. If by this operation these apertures are brought, without fur-

ther adjustment, into proper register then the bolts 4 are inserted and screwed tight home.

If the knife requires a longitudinal adjustment this may be accomplished by simple manual rotation of the two discs simultaneously in the required direction.

If one end or the other of the knife requires relative raising or depressing in order to bring about a correct register of the bolt receiving openings, this may be quickly accomplished by 10 rotating one or the other of the discs as may be necessary to produce the proper vertical movement of that end of the knife.

It may be here noted to advantage that during all adjustments of the knife by rotary movement 15 of one or both of the discs the knife is resting frictionally not only against the upper surfaces of the discs but also against the flat surface of the clamping bar. When both of the discs are simultaneously rotated in one direction the combined frictional grip of the two discs upon the knife is sufficient to overcome the frictional resistance between the knife and the surface of the clamping bar so that the knife will move 20 endwise or horizontally.

If however only one of the discs is rotated, while the other remains motionless, the frictional grip of the single moving disc is not sufficient to overcome the combined frictional grip 25 between the knife and the stationary disc, and between the knife and the clamping bar. Thus a rotating movement of only one disc will not produce endwise movement of the knife but it will produce a vertical movement of the adjacent end portion of the knife due to the eccentric 30 mounting of the disc.

A workman, gripping the two discs, one by one hand and the other by the other hand, may thus quickly, easily, accurately and safely perform the required fine adjustment of the knife, both horizontally and vertically, to bring it into register 40 with the bolt holes of the bar A.

After the knife has been relatively roughly adjusted, by reason of the upward movement of the clamping bar, and after it has been relatively finely adjusted, if required, as by manual operation of one or both of the discs, then the bolts 4 are inserted and tightened.

After the knife has been properly clamped by the bolts 4 then the present attachment is removed from the clamp bar H so as to leave the face of said bar unobstructed for the free movement of the knife in the performance of its normal functions.

The attachment contemplated by the present 55 invention, that is the discs 7 and 8 and their retaining bolts 9, is of simple and inexpensive construction, and its manner of use is of a simple and practical character requiring not greater than the ordinary intelligence of the average 60 workman.

As many changes could be made in this construction without departing from the scope of the invention as defined in the following claims, it is intended that all matter contained in the 65 above description, or shown in the accompanying drawing, shall be interpreted as illustrative only and not in a limiting sense.

Having thus described my invention, what I claim as new and desire to secure by Letters 70 Patent is:—

1. An attachment for a paper cutting machine, said attachment being adapted to constitute a temporary support for the detachable knife of such machine, said attachment consisting of a 75

pair of separately formed discs having pivot openings therethrough, a pair of bolts extending through said pivot openings adapted to pivotally connect said discs in position upon the machine,
5 said pivot openings being eccentric with respect to the periphery of said discs, said discs being rotatable about said bolts to lift said knife to different elevations and said discs having means to facilitate their manual rotation independently
10 of each other upon their respective supporting bolts.

2. An attachment for a paper cutting machine, said attachment being adapted to constitute a temporary support for the detachable knife of such machine, said attachment consisting of a plurality of separately formed discs having pivot openings therethrough, bolts extending through said pivot openings adapted to pivotally connect said discs in position upon the machine, said pivot openings being eccentric with respect to the periphery of said discs and said discs being rotatable about said bolts to lift said knife to different elevations.

3. A paper cutting machine including in combination a knife carrier, a knife, means for detachably securing said knife to said carrier, a clamping bar adjacent said knife, said knife carrier

and clamping bar being relatively movable, means for independently moving said knife carrier and clamping bar respectively and means mounted on said clamping bar for supporting said knife when detached from said carrier, the surface of said supporting means engaging with said knife being vertically movable with relation to said clamping bar to lift said knife to different elevations.

4. A paper cutting machine including in combination a knife carrier, a knife, means for detachably securing said knife to said carrier, a clamping bar adjacent said knife, said knife carrier and clamping bar being relatively movable, means for independently moving said knife carrier and clamping bar respectively, a plurality of separately formed discs having pivot openings therethrough, bolts extending through said pivot openings and pivotally connecting said discs to said clamping bar, said pivot openings being eccentric with respect to the peripheries of said discs, said discs being adapted to support said knife when it is detached from said carrier and said discs being rotatable about said bolts to lift said knife to different elevations.
